(57) **CLAIM**

The ornamental design for an electrical connector, as shown and described.

DESCRIPTION

FIG. 1 is a front isometric view for an electrical connector. FIG. 2 is a front view of the electrical connector of FIG. 1. FIG. 3 is a side of the electrical connector of FIG. 1. FIG. 4 is a rear view of the electrical connector of FIG. 1. FIG. 5 is another side view of the electrical connector of FIG. 1.

FIG. 6 is a top view of the electrical connector of FIG. 1; and,

FIG. 7 is a bottom view of the electrical connector of FIG. 1.

The broken line portion of the figure drawings is included to show portions of the electrical connector that form no part of the claimed design.

1 Claim, 7 Drawing Sheets
